MACHINE FOR FORMING GLUED FOLDING BOXES

Edward J. Pagendarm, San Mateo, Calif., assignor, by mesne assignments, to Atlas General Industries, Inc., a corporation of Massachusetts

Filed Mar. 6, 1959, Ser. No. 797,688
34 Claims. (Cl. 93—51)

This invention relates to the art of making folding boxes by folding an appropriately shaped box blank and adhesively securing certain of its portions together in box forming position.

Conventional box making machines comprises basically a conveyor which moves an initially flat box blank past adhesive applying and folding devices, whereafter the box passes into a pressure section in which the glued portions are maintained under pressure until the adhesive bond has become sufficiently strong to permit the box to be discharged from the machine. These machines are relatively extended and occupy a large amount of floor space.

It has been proposed to reduce the length of the box making machine by use of a box folding mechanism of the plunger and die type, preceded by a conventional conveyor portion flanked by prefolding mechanism and glue wheels. In the known machines one purpose of the prefolding mechanism is to move certain portions of the box blank out of engagement with the glue wheels and another purpose is to prepare the blank for the subsequent folding operation performed in the plunger and die mechanism.

Adhesive applicators of the wheel type have numerous disadvantages, among which may be mentioned the tendency of the wheels to pick up board dust, which is ever-present in a box plant, and necessitates frequent cleaning of the glue applicator. Glue wheels exposed the adhesive to the atmospheric air by reason of the large surface of the adhesive coated area of the wheel and, as a consequence, the adhesive oxidizes and deteriorates rapidly. The nightly shut-down of the machine causes portions of the glue wheels to dry up, a disadvantage which is noticeable even after relatively brief shut-down, such as the lunch hour shut-down of the machine.

Conventional glue wheels generally apply the adhesive in strip form from one outer edge of the flap or panel to which the adhesive is applied to the opposite edge. This is normally not disadvantageous where there is a substantial lapse of time between the application of the adhesive and the application of pressure in the pressure section, and where the pressure is neither severe nor applied so suddenly that the adhesive near the edges of the blank or panel is squeezed out beyond the edge of the panel.

In a machine of the plunger and die type, however, a relatively great compressive force is applied rather suddenly by contraction of the die, resulting in squeezing of adhesive beyond the edge of the flap or panel, thereby soiling the box and the die. Adhesive deposited on the die surfaces interferes with the operation of the machine and necessitates periodic shut-down of the machine for cleaning purposes.

The present invention permits a box folding and gluing machine to be built of very compact size requiring a floor space of the order of five by five feet.

Folding and compression of the box is accomplished by a plunger and die mechanism into which the flat blank is fed. A measured quantity of adhesive is applied to the blank in a predetermined pattern, which is preferably so laid out that the adhesive is never squeezed beyond the edges of the flaps or panels to be adhesively secured, even though the compressive force is very high and is suddenly applied.

2

The invention permits use of very fast drying adhesive compositions by depositing the adhesive in slow drying drop or bead form, rather than as a quick drying thin film exposed to air. The drops or beads are converted into the form of a thin film by contact of the surfaces which are to be adhesively secured. This contact takes place under high pressure and causes the deposited quantity of adhesive to be spread out as a thin film.

The present invention permits the time between the application of the adhesive and the actual formation of the glue bond to be made extremely short, of the order of a fraction of a second. The high compressive force which is applied to the glue bond produces a very thin glue film between the surfaces to be adhered. Such a film sets almost instantly and permits the box to be discharged immediately thereafter. This, in turn, results in a high productive rate.

Preferably the step of applying adhesive is combined with the step of prefolding the blank. This permits the adhesive applicator to be constructed as a portion of a prefolding mechanism against which the flat blank is moved. The transport of the blank may be accomplished by a combination feeder and plunger which comes to rest sufficiently long to permit a pattern of adhesive to be applied to a stationary blank. Preferably a feeder is employed which is distinct and separate from the plunger which subsequently forms the box. In the preferred arrangement the blank is moved into the path of the plunger by the blank feeder which then releases the blank so that the blank comes to rest for a brief moment during which the adhesive pattern is applied far more accurately than if the blank were in motion.

The invention further makes possible an arrangement for discharging adhesive only when a blank is present, so that the discharge of adhesive is suspended when the supply of blanks is interrupted.

At first impression it would seem a simple matter to accomplish this by installing a device responsive to the presence of a blank at the station where adhesive is to be applied, in the present case the mouth of the folding die. In actual practice, however, this is not practicable in a rapidly operating machine because the time is not sufficient to render the adhesive applicator effective or ineffective once the blank has arrived at the mouth of the die. The moving parts of the control mechanism have a certain mass and present acceleration and inertia problems which do not permit actuation in response to a signal developed at the mouth of the die.

According to one aspect of the present invention a control signal is developed during the feeding of the blank by the mechanism which transports the blank from the magazine to the die. Here a problem is encountered due to the fact that the blank feeder has actually released the blank at the moment adhesive is to be applied. The blank feeder itself therefore is in the same condition at that moment as if no blank had been fed during the preceding cycle. According to the present invention the signal is derived prior to the application of the adhesive and is then stored until after release of the blank by the feeder. This arrangement leaves sufficient time for the mechanism which controls or operates the adhesive applicator to be moved into an operative or inoperative position depending on the presence or absence of a blank on the feeder prior to the arrival of the blank at the mouth of the die.

These and various other features and advantages of the invention will appear more fully from the detailed description which follows accompanied by drawings showing, for the purpose of illustration, a preferred embodiment of the invention. The invention also resides in certain new and original features of construction and combination of elements hereinafter set forth and claimed.

Although the characteristic features of this invention which are believed to be novel will be particularly pointed out in the claims appended hereto, the invention itself, its objects and advantages, and the manner in which it may be carried out may be better understood by referring to the following description taken in connection with the accompanying drawings forming a part of it in which:

FIG. 1 is a perspective view of a partially assembled machine for carrying out the invention;

FIG. 2 is an elevational view of a portion of the drive mechanism of the machine of FIG. 1;

FIG. 3 is a perspective view of the machine of FIG. 1 at an advanced stage of assembly showing the blank feeder mechanism and a portion of the power mechanism for contracting the die;

FIG. 4 is a perspective bottom view of the power mechanism of FIG. 3;

FIG. 5 is a perspective view of the blank feeder, the plunger and the die of the machine and illustrates a phase of the operation in which a flat blank approaches the glue applying mechanism above the die;

FIG. 6 shows the blank prefolded at a moment shortly prior to the release by the feeder and prior to the application of adhesive;

FIG. 7 illustrates a later phase of the operation at which the plunger strikes the blank while the feeder approaches the magazine to pick up the next blank;

FIGS. 8, 9 and 10 illustrate successive stages of the forming operation performed on the box, FIG. 10 showing the position in which the plunger as well as the oscillating drive bar has reached its lowest position;

FIG. 11 is a perspective view of a pneumatic actuating mechanism between the drive bar and the plunger proper;

FIG. 12 is a perspective view of the drive mechanism of the machine including the actuator for the glue pump;

FIGS. 13, 14 and 15 illustrate different positions of adjustment of the mechanism for interrupting the feeding of adhesive, FIG. 13 showing a position in which adhesive is about to be fed, FIG. 14 showing the position in which adhesive is being fed and FIG. 15 showing a position in which no adhesive is fed;

FIGS. 16 to 20 are diagrammatic illustrations of operating conditions under which adhesive is being fed and other conditions under which no adhesive is fed;

FIG. 21 is a perspective view of the die with a box therein after withdrawal of the plunger;

FIG. 22 is an elevational view partly in section of a hydraulic snubber; and

FIG. 23 is a diagram of the electric circuit of the machine.

In the following description and in the claims various details will be identified by specific names for convenience. The names, however, are intended to be generic in their application. Corresponding reference characters refer to corresponding parts in the several figures of the drawings.

The drawings accompanying, and forming part of, this specification disclose certain details of the invention for the purpose of explanation of its broader aspects, but it is understood that the details may be modified in various respects without departure from the principles of the invention and that the invention may be incorporated in other structures than the one shown.

FIGURE 1 shows the machine in a state of partial assembly so that portions of the drive may be seen more clearly. The machine comprises a framework 11 supporting a motor 12 on an adjustable mount 13. The mount 13 forms an element of a variable speed drive 14 whose other major element is a V-belt pulley 15 of variable effective diameter.

A V-belt 16 extends over a driven pulley 17 carrying a sprocket gear (not visible) from which a chain 18 extends to a sprocket gear 19 on a pinion shaft 20.

When the speed of the drive is reduced by reducing the effective diameter of the pulley 15 the resulting slack of

the belt 16 is taken up by moving the motor forward towards the observer on the adjustable mount 13.

The pinion shaft 20 carries a pinion 21 meshing with a large gear 22 on a crank shaft 23 carrying a crank 24 on either end. The crank is not visible in FIG. 1 but shown in FIG. 2.

The mechanism about to be described is mounted on both sides of the machine and comprises a crank 24 connected by a lower link 25 to a lower oscillating arm 26 whose one end is pivoted to a plate 27 of the framework at 28 and whose other end is pivotally connected to a connecting rod 29. The upper end of the connecting rod 29 is pivotally connected to a cross head member 30 at 31 (see FIG. 3). The cross head member 30 is vertically 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 lating gripper bar 40 is complex and is disclosed in detail in the above mentioned Lefief patent.

Briefly, the motion of the bar 40 is first substantially horizontal towards the observer during which phase a blank standing on edge is separated from a stack of blanks behind it. After the first substantially translatory motion the bar 40 performs a rotary motion above the pivots 42 whereby the blank is turned substantially 90 degrees, or less, until it is horizontal. The second phase of the motion of the bar 40 is followed by a third phase during which the blank is moved in a substantially vertical direction, parallel to itself, whereafter the bar 40 stops and the feeding mechanism releases the blank. The bar then moves through a return cycle, first upward and away from the blank, then on an arc into the position in which it is shown in FIG. 1 and then away from the observer towards the stack of blanks in order to pick up the next blank. The location of the magazine is best seen in FIGS. 6 to 11. FIG. 5 shows the blank and bar 40 during the rotary phase of the motion, FIG. 10 shows the position in which a blank is about to be removed from the magazine and FIG. 6 shows the position in which the blank is about to be released in a substantially horizontal position.

With an understanding of the basic construction and operation of the drive mechanism it will now be easy to follow the construction and the operation of the specific mechanisms for handling the blank, applying adhesive thereto, folding it into box shape and subjecting the shaped box to compression to set the adhesive sufficiently to permit the box to be discharged.

The box forming mechanism comprises a forming die including means for expanding and contracting it for the purpose of first admitting a formed box into the throat of the die and then subjecting it to compressive force.

The die mechanism is best explained by first turning to FIG. 3 showing the mechanism in a state of partial assembly installed in the machine, and to FIG. 4 showing the compression mechanism standing up on end so that its construction and operation can be followed.

Referring first to FIG. 3, the compression unit comprises a heavy box frame 58 having side members 59 with flanges 60 resting on the front arms 53 of the castings 51 and held in place by the knurled nuts 54. The side members 59 are connected by transverse top plates 61 and bottom plates 62 welded thereto, the whole structure being sufficiently strong to withstand forces of the order of several tons. Two pivot pins 63 extend through the box frame in the back and pivotally support jaw arms 64 and 65, the other ends of which carry front pins 66 extending through apertures 67 in the transverse bottom plate 62.

A hydraulic cylinder 68 provided with an extension 69 is pivotally connected to the right jaw arm 65 by means of the right front pin 66. A piston 70 is slidable in the cylinder and its piston rod 71 extends through a stuffing box 72 to the outside. The piston rod is pivotally connected to the left jaw arm 64 by the left front pin 66.

The piston subdivides the cylinder space into a first chamber to which a flexible pressure line 73 leads and a second chamber to which a flexible pressure line 74 extends. It is immediately apparent that excess pressure in line 74 causes the piston to travel to the right as a result of which the jaw arms 64 and 65 are drawn together, whereas excess pressure in the pressure line 73 causes the piston to travel to the left and the jaw arms to move apart. A pair of stroke limiting screws 75 are provided for limiting the opening movement.

A pair of jaws 76, 77 are mounted for parallel movement on rods 78 in the box frame. Only the rear rod is visible, the front rod being hidden under the transverse plates. The jaws 76 and 77 have substantially cylindrical extensions 79 secured thereto which are grasped by links 80. Each link has a closed end through which the center pin 81 in each jaw arm extends and an open end which

grasps the cylindrical extensions 79. By an exchange of a short link by a longer link the spacing of the jaws 76 and 77 may be reduced to handle a box of small size, whereas replacement of the link 80 by a shorter link enlarges the space between the jaws 76 and 77 to accommodate a larger box.

The mounting of the hydraulic cylinder within the box frame 58 is a floating mounting insuring application of equal force to both jaws 76 and 77.

10 A floating mounting, however, does not automatically insure simultaneous application of force in both directions, in that force may be applied sooner to one jaw than to the other. This would also subject a plunger in the die to one-sided blow. To prevent this from hap-

15 pening centering means are provided which, in the illus- trated form, comprise a centering arm 82 pivotally mounted to the box frame at 83. Connecting rods 84 and 85 extend from the centering arm 82 to the bottom ends of the front pins 66 as is particularly well visible in FIG. 4.

20 The linkage comprising the centering lever with its two connecting rods insures an equal distance of travel of both jaws 76 and 77 with respect to the central axis of the frame and simultaneous application of force at both jaws.

25 A hydraulic pump driven by a separate electric motor of approximately two horsepower size is enclosed in a pump housing 86 shown in FIG. 3 and hydraulic lines extend from the pump to a hydraulic control valve 87 combined with a solenoid actuator from which a cable 30 88 extends to a control switch 89 (FIG. 12). The control switch includes a movable arm on which a roller 90 is mounted resting on the periphery of a control cam 91 on the crank shaft 23.

The compression unit and its controls form the subject matter of a separate copending application, serial No. 797,806, filed March 6, 1959, now Patent No. 2,997,929. For the description of the present invention it is sufficient to state that the control cam 91 operates the control switch 89 in such a way that the hydraulic 40 control valve 87 first directs the application of high hydraulic pressure through pressure line 74 to move the jaws 76 and 77 together, whereafter the hydraulic control valve 87 directs the application of a lower hydraulic pressure through pressure line 73 to move the jaws apart.

45 The jaws 76 and 77 have tapped holes 92 into which mounting bolts 111 may be screwed (see FIG. 5) for attaching pressure plates 110 matching the exact size of the wall panels of the box to which pressure is to be applied. The pressure plates are preferably slightly 50 smaller than the wall panels of the box so that any excess adhesive which is squeezed out of the gluing joint will not be deposited on the plates and transferred to subsequent boxes.

FIG. 3 also shows an empty magazine gate 93 attached to the magazine supporting plate 52. Box blank supporting bars 94 extend from the magazine gate to the rear. The bars support flat box blanks standing on edge and the magazine gate 93 is so dimensioned that it retains the frontmost blank by a slight marginal overlap sufficient to hold the blanks in place, but permitting withdrawal of blanks, one at a time, by the blank feeder which includes suction cups 95. The suction cups are mounted on a feeder frame 96 including lateral bars 97 attached to the feeder bar 40. The previously mentioned flexible tubing 57 carries vacuum to the cups 95. The magazine construction is disclosed in detail in the Patent 2,642,285 to Baker et al. of June 16, 1953.

55 FIG. 5 illustrates the plunger and die mechanism fully assembled, in condition for operation.

70 A die frame 98 is mounted on the box frame 58 by four corner bolts 99, carrying knurled nuts 54. The die frame is provided with curved front and rear die plates 100 and 101, respectively, for folding the front panel and the back panel of the folding box, and side plates 75 102 and 103 for folding the end panels of the box blank

into box forming position. All four plates have downwardly curved lips defining a substantially rectangular die throat 104 above which an appropriately shaped plunger 105 is mounted.

The plunger 105 is supported on the plunger drive bar 33 by a pneumatic mechanism later to be described. At this point it is sufficient to state that vertical movement of the bar 33 causes the plunger 105 to move into and out of the die throat in timed intervals.

The front and rear die plates 100 and 101 have slots in them through which spring urged stripper fingers 106 protrude whose purpose it is to prevent a formed box from being withdrawn upwardly when the plunger 105 moves out of the die. The fingers 106 normally protrude into the rectangular throat space, but may be pushed back by a box blank entering the throat. The plunger is appropriately recessed at its front and rear surfaces as shown at 107 to clear the stripper fingers in the event the plunger moves into and out of the die without the blank and to prevent the fingers from catching the plunger during its return stroke in normal operation.

The front and rear surfaces of the die carry opposed box wall deflectors 108 which, in the illustrated form of the machine, have the shape of a spring loaded ball. Corresponding vertical grooves 109 in the plunger body provide clearance between the box wall deflectors and the plunger. The deflectors bow in the front and rear walls of a completed box immediately after withdrawal of the plunger so that the distance between the bowed-in portions of the front and rear walls becomes less than the corresponding dimension of the bottom panel of the next box to be formed. As a result, the next box seats on the top edge of the bowed-in wall portions of the last formed box and causes the last formed box to be ejected from the die.

FIG. 21 illustrates the bowing in of the box, the action of the stripper fingers 106 and also shows details of the construction of the die.

Glue heads 112 are mounted at the four corners of the die. Each head is mounted at an angle with respect to the surface of the die frame 98 and includes a front plate 113 having a plurality of discharge apertures 114 arranged in a pattern. Each discharge aperture 114 is adapted to discharge a certain volume of adhesive which is supplied to the hollow interior of the glue head by an adhesive supply duct 115. A reservoir 116 contains liquid adhesive which is withdrawn from the reservoir through a duct 117 leading to a glue feeding device, preferably in the form of a positive displacement pump which then pumps adhesive under pressure through the adhesive supply ducts to the several glue heads.

The discharge apertures of the glue heads are normally open to permit periodic discharge of adhesive in response to periodic actuation of the pump, but means are provided for closing some or all of the apertures by moveable pins mounted interiorly of the heads. The glue head nearest the observer in FIG. 21 is provided with a clear plastic cover 118 showing three spring urged blocks 119, 120 and 121 inside the head, each block having a plurality of pins 122 at its front. A shaft 123 carrying a knurled knob 124 at its upper end and a cam or eccentric (not visible) at its lower end serves to adjust the three blocks in such a manner that the pins of one, two or three blocks are withdrawn from their respective discharge apertures whereby the size of the glue pattern may be varied. In one extreme position the blocks with their respective pins close all the discharge apertures, so that clogging of the apertures by drying adhesive is prevented.

Application of adhesive to the flaps F takes place shortly after the flaps F are folded into upwardly slanted position by the feeder and before the plunger 105 engages the blank. Each discharge aperture of the applicators discharges a droplet of adhesive. These droplets are applied in a pattern which is preferably of such outline that no

droplets are deposited within a marginal zone of the flaps F.

The adhesive applicator forms the subject matter of a separate copending application, Serial No. 797,792, filed March 6, 1959.

The die frame 98 further supports movable catches 125, each catch comprising a base bracket 126 supporting a latch 127 on a pivot 128, the latch being normally urged towards the throat of the die by a spring 129. The catches serve to hold a blank securely above the throat of the die after the blank is deposited by the blank feeder so that the blank does not change its position by reason of air drafts, vibration, etc. during the approach of the plunger 105.

FIG. 5 shows the plunger 105 during its upstroke and also shows the feeding mechanism moving a blank B towards the die. In the position shown in FIG. 5 the gripper bar 40 of the feeder performs a rotary motion and moves on an arc to which the plane of the blank B is substantially tangential.

FIG. 6 illustrates the end of the feed stroke during which the feeder performs a translatory motion to deposit the blank above the die throat. During this phase of the feeding motion the four glue flaps F of the blank first strike the four glue heads which act as prefolding elements and cause the flaps to be folded into an angular position with respect to the remainder of the blank B. At the end of the feed stroke the unfolded portion of the blank comes to rest on the horizontal portions of the die plate as seen, for example, at 100, and the blank snaps underneath the four catches 125 which hold it securely in place during the subsequent return motion of the feeder.

In the prefolded position, the flaps F assume substantially the same angle as the front plates 113 of the glue heads and either rest against the glue heads or are spaced therefrom by a very narrow gap of the order of a millimeter or less. This can simply be accomplished by setting the glue heads at a slant slightly different from the slant of the flaps F.

The blank B is now released by an appropriate vent valve in the vacuum line 57 leading to the suction cups 95. The valve, which will be referred to later in connection with FIGS. 17 to 21, admits atmospheric air into the line 57 near the vacuum cups as a result of which the cups 95 release the blank. The blank feeder then begins its return stroke and moves out of the way of the plunger 105 which descends to strike the bottom panel of the box blank as shown in FIG. 7.

During the time the blank B is at rest the glue pump makes a feed stroke to discharge a measured quantity of adhesive through the four glue heads 112. As a result a pattern of predetermined outline of adhesive is deposited on each of the flaps F. Details of the mechanism for actuating the glue pump will later be described in connection with FIGS. 17 to 21.

As the plunger enters the die the front and back panels whose edges were caught under the catches 125 are withdrawn therefrom and are folded upwardly as shown in FIG. 8. The glue flaps F remain at an angle with respect to the front and back panels of the box and are being folded about the plunger briefly prior to the folding of the outer side walls of the box into upright position on top of the glue flaps F.

FIG. 9 shows the plunger 105 in a position in which the folding of the box blank B is nearly complete and the box has entered the throat of the die except for its top portion which is still visible above the front plate 100 and the side plate 102.

FIG. 10 shows the plunger at the bottom of its stroke and the plunger drive bar 33 at its lowest position. At this instant the compression unit is actuated by applying high pressure through the line 74 to contract the die. The pressure which is applied is of the order of 2000 pounds per square inch applying a force of the order of five to six tons at the jaws 76 and 77. The jaws press against the side walls of the box with their pressure plates 110

(see FIG. 3 showing the jaws and FIG. 5 showing the pressure plate). The applied pressure causes the adhesive to be distributed over the flaps F as a very thin film which begins to set immediately due to the fact that the amount of solvent to be absorbed by the board per unit of area is very small. Under these conditions the adhesive becomes highly tacky immediately and produces a secure bond, although the application of pressure is quite short, of the order of a fraction of a second.

The travel of the jaws is short and is maintained as small as possible by an appropriate setting of the stroke limiting screws 75 shown in FIG. 3.

The stroke centering device, more particularly the centering lever 82 and the connecting rods 84 and 85 (FIG. 4) insure simultaneous application of the force by both jaws 76 and 77 of the compression unit, so that the plunger is not subjected to a lateral blow by one jaw striking before the other.

Although an application of compressive force during a period of the order of one-fifth of a second is satisfactory, it is preferred to maintain the force as long as is consistent with the rate of operation of the machine.

As previously mentioned, the plunger drive bar 33 moves up and down continuously and never comes to rest except at the return points at the ends of the up and down stroke, respectively. It is not practicable to arrest the plunger drive bar during the period of application of compressive force due to the mass of the mechanism which would have to be stopped and then accelerated from rest.

It is thus readily seen that it is not practicable to mount the plunger directly on the drive bar 33 which continues to move while the plunger must remain at rest during the compression cycle. Also, it is necessary to accelerate the plunger gradually from a position of rest without a resulting pounding in the drive mechanism by reason of the inertia of the masses involved.

A pneumatic mechanism is provided which suspends the plunger from the drive bar. This mechanism forms the subject matter of a separate copending application, Serial No. 797,676, filed March 6, 1959, now Patent No. 2,997,928.

The plunger drive bar 33 (FIGS. 10 and 11) carries two brackets 130 and 131 on which a common base plate 132 is mounted. The base plate 132 carries two vertical cylinders 133 and 134, each containing a piston 135 and 136 whose piston rods 137 and 138 extend through the top of the cylinders and are connected by a piston plate 139.

The top ends of the cylinders 133 and 134 are held in place by a top plate 140 which is rigidly connected to the base plate 132 by four spacer rods 141. The front rods are visible in FIG. 11 while a rearward rod is also seen in FIG. 10. Two slide bearing sleeves 142 and 143 are also held between the base plate 132 and the top plate 140. Plunger rods 144 and 145 extend slidably through the sleeves 142 and 143 and carry a plunger plate 146 at their lower ends. The plunger 105 is secured to the plunger plate 146 by a bolt 147.

The pistons 135 and 136 divide the cylinders into upper chambers and lower chambers, the upper chambers being in communication with the atmospheric air through air filters 148 which keep out dust. The lower chambers are in communication with the atmosphere through similar filters 148. Valve assemblies 149 and 150 are interposed between the lower chambers and the atmosphere, the assembly 150 being mounted upside down with respect to the valve assembly 149. Comparing FIG. 10 with FIG. 11 it will be noted that the valve assemblies 149 and 150 were rotated 90 degrees in FIG. 11 with respect to the position in which they are shown in FIG. 10. This was merely done to show the inverted mounting in both figures which would not be noticeable if the assemblies had not been rotated for the purpose of illustration.

Each valve assembly comprises basically a housing tapped at both ends for threaded connection with appro-

priate fittings. Intermediate its ends the housing is divided by an internal cross wall not shown in the drawings. The internal wall has two apertures through which the upper portion of the housing may communicate with the lower portion. One of these apertures is variable in size by a needle valve N, the other is controlled by a check valve C. The needle valve permits restricted passage of air through the valve assembly in the direction of the axis of the valve housing. The check valve permits relatively free flow of air in one direction, but seals its passage when the air flows in the opposite direction.

As a result of the inverted mounting of valve assembly 150 with respect to the assembly 149, atmospheric air enters freely into the lower chamber of the cylinder 134 when its piston moves upwardly, whereas downward motion of the same piston meets with resistance because air being forced out of the lower chamber causes the check valve C to close and can escape only through the restricted needle valve N. Thus downward motion of the piston 20 within the right cylinder 134 is restrained whereas upward motion is unrestrained.

The reverse applies with respect to the piston within the left cylinder 133. Upward piston motion, causing air to enter its lower chamber, is restrained because air can only enter through its needle valve N while its check valve C is closed. Downward motion, however, causing air to escape from the lower chamber, is unrestrained because the air escapes freely through the check valve C.

An adjustment of the needle valve N permits any desired degree of restraint to be imposed on the upward motion and the downward motion of the pistons with respect to the cylinders and thus upon the plunger 105 with respect to its drive bar 33. The restraint is of an elastic nature due to the compressibility and the expandability of air.

In order to prevent the pistons from bottoming in the respective cylinders 133 and 134 a pair of buffers 151 are mounted on the top plate 140 on which stops 152 on piston plate 139 may seat.

It was previously mentioned that the downward motion of the plunger 105 is arrested in the position in which compressive force is exerted on the folding box.

In order to prevent sudden stops of the plunger from producing a corresponding impact on the drive a hydraulic 45 snubber mechanism is provided comprising a snubber cylinder 153 mounted on the framework 11 on the machine and a striker pad 154 on the piston plate 139. When the striker pad 154 seats on the rod 155 of the snubber piston 158 enclosed in the snubber cylinder 153 (see also FIG. 23), liquid 159 is displaced past the piston through a narrow passage 160 which is restricted increasingly the farther the piston moves. A reservoir 156 is in communication with the snubber cylinder 153 through a hydraulic line 157. A spring 161 returns the piston 158 to a normal rest position. The variable flow resistance in the liquid passage causes the end of the snubber 155 to offer increasing resistance to the downward motion of the piston plate 139, and arrests plunger 105 gently.

It is now readily seen that once the plunger 105 has 60 reached its lowest position in the throat of the folding die, and is temporarily clamped by reason of the action of the compression unit, the plunger drive bar 33 may start its upward motion without delay. During the upward motion of the bar 33 the cylinders 133 and 134 move into an upward direction with respect to their pistons which are at rest by reason of being attached to the plunger. During this motion air is compressed in the lower chamber of the cylinder 134 and escapes only slowly because of the restriction of air flow by the needle valve N of the assembly 150. This compressed air represents a resilient driving force which drives the plunger 105 upwardly as soon as the compressive force by the compression unit is released. This action is gentle and continues until the pistons are 70 raised so far that the stops 152 seat on the buffers 151,

whereafter the upstroke of the plunger 105 continues at the same rate as the upward motion of the drive bar 33.

When the drive bar 33 comes to rest in its upper return position, the plunger 105 is permitted to continue traveling in an upward direction for a certain distance, thereby separating the stops 152 from the buffers 151 while the drive bar 33 moves downwardly. The plunger 105 comes to rest in a top position and its motion is then reversed by the creation of a vacuum in the left cylinder 133 into which air can enter only slowly because of the restriction to air flow imposed by its needle valve N.

The mechanism for actuating the glue pump 162 is shown perspective in FIGS. 13 to 15 and diagrammatically in FIGS. 16 to 20. A platform 163 is tiltably mounted on the framework 11 by means of an eccentric pivot 164 held in a bracket 165. The eccentricity of the pivot permits the end of the platform 163 nearest the observer to be raised and lowered for the purpose of adjustment. The adjustment is facilitated by a pointer 166 movable relatively to, and readable on, a setting dial 167 on the bracket 165. The far end of the platform 163 has a downwardly extending follower bracket 168 carrying a roller 169. The roller bears against the periphery of a pump actuating cam 170 on the crank shaft 23 (FIG. 12). The cam 170 has an elevated portion 171 which lifts the roller 169 and causes the platform 163 to be tilted upwardly once for each revolution of the shaft 23.

A rail 172 is welded to the platform 163 at 173 and supports a carriage 174 which is slideable lengthwise with respect to the rail 172. A pneumatic servo-motor 175 is mounted on the platform 163 and comprises a cylinder 176 within which a piston 177 is movable (FIG. 16). A spring 193 tends to move the piston 177 to the left in FIG. 16 and towards the observer in FIG. 13, whereas vacuum applied to the line 178 results in movement of the piston in the opposite direction. The carriage 174 is connected to the servo-motor piston by a pin 179. The carriage 174 has a top surface 180 which is slideable into and out of engagement of an actuator 181 of a glue pump 182 connected to the reservoir 116 of adhesive by the adhesive supply ducts 115.

When a vacuum is applied to the servo-motor 175 through the line 178, the servo-motor moves the carriage in a direction away from the observer of FIG. 14, or to the right in FIG. 16 so that an upward tilt of the platform 163 causes the top surface 180 to engage the glue pump actuator. As a result, adhesive is pumped to the glue heads and is discharged through their respective discharge apertures 114. The volume of adhesive may be varied by adjusting the pump stroke. When the eccentric pivot 164 is set high, more adhesive is pumped than when the pivot is set low. The dial 167 may therefore be calibrated in volumetric units.

A signal may be derived from the pneumatic blank feeder for controlling the operation of the glue pump in such a manner that adhesive is discharged only when a blank is fed to the die, whereas the feeding of adhesive is interrupted when the supply of blanks is interrupted.

As previously explained, the vacuum cups of the blank feeder have released the blank at the time adhesive is applied, so that the pressure condition at the vacuum cups at a certain moment cannot be directly utilized for control of the glue pump at the same moment.

It is necessary for this reason to derive the control signal during the period the blank feeder moves towards the die, either with or without a blank, and to store this signal until the latter moment of the glue pump is to be actuated. This is accomplished by an arrangement illustrated in FIGS. 16 to 20. FIGS. 16 and 17 illustrate the condition of normal blank feeding and FIGS. 18 to 20 illustrate a condition in which the feeding of blanks is interrupted.

FIG. 16 shows a constriction 183 in the suction line 56 extending from the vacuum pump 55. This constriction need not actually be present in the actual installation but

merely represents, for the purpose of illustration, the flow resistance of the line 56, as a result of which a measurable change in vacuum pressure occurs at 184 depending on the presence or absence of a blank B on the suction cup 95.

The pressure condition is illustrated by a vacuum gauge 185, which also need not be present in the actual installation, but which illustrates the presence of a low vacuum when its pointer is at the left and a high vacuum when its pointer is at the right.

5 The control valve 186 is mechanically coupled with the blank feeder mechanism in such a way as to remain in the position shown in FIG. 16 during the picking up and transporting of the blank from the magazine to the die whereafter the valve is moved into the position shown in FIG. 17 to vent the line 57 to the atmosphere at 162. This causes the blank to be released.

10 FIG. 18 illustrates the condition in which the blank feeder makes its feed stroke without a blank in the event 20 the supply of blanks in the magazine is exhausted. While the valve 186 is in the position shown in FIG. 18 atmospheric air enters the suction cup 95 and causes the vacuum at the point 184 to drop, as is indicated by the position of the pointer of the gauge 185. This drop in 25 the vacuum is not overcome by the pump 55 due to the fact that the line 56 has considerable flow resistance, here represented by the restriction 183.

15 Turning now to the actuating mechanism for the glue 30 pump, it is seen that the cam 170 actually comprises three portions of elevation shown by concentric circles. There is a depressed portion 187 of minimum radius, an intermediate portion 188 of intermediate radius and an elevated portion 171 of maximum radius, the latter being the portion which actuates the glue pump 182.

20 A catch 189 is pivotally mounted at 190 on the framework of the machine (see also FIG. 15) and has a stop 191 limiting its movement in one direction. This catch is so mounted that it engages a shoulder 192 on a carriage 174, if the cam follower 169 has ascended above the depressed cam portion 187.

25 Considering the inclination of the platform 163, the carriage 174 may slide freely beneath the catch 189 when the cam follower 169 rests on the depressed portion 187 of the cam 170, as shown in FIG. 18.

30 When the platform 163 is raised into the intermediate position shown in FIG. 19, in which the cam follower 169 rests on the intermediate portion 188 of the cam, the catch 189 strikes the shoulder 192 of the carriage and arrests it. The catch maintains the carriage 174 arrested while the cam follower moves onto the elevated portion 171 of the cam.

35 In the position in which the carriage 174 is arrested by the catch 189, the pump actuator 181 clears the carriage 174 and is not lifted by the top surface 180, as is clearly seen in FIGS. 18, 19 and 20.

40 The operation of the signal producing and signal storing mechanism is as follows:

45 It may first be assumed that the operation of the machine is normal in the sense that a blank B is being transported by the suction cup 95 from the magazine to the die. During the feed stroke high vacuum prevails in the vacuum lines 56 and 57 and the vacuum is transmitted to the servo-motor 175 by the signal line 178. The piston of the servo-motor is pulled in against the action of the spring 173 and the top surface 180 is moved underneath the glue pump actuator during the period the blank is being transported to the die. During this period the cam follower 169 first rests on the depressed cam portion 187, permitting the carriage 174 to move beyond the catch 189. Thereafter the platform 163 is raised by the follower 169 which moves onto the intermediate portion 188. This causes the catch 189 to tilt without interfering with the carriage 174.

50 The blank B is subsequently dropped by venting the suction line 57 of the cup to the atmosphere at 162, as

shown in FIG. 17. This does not change the vacuum in the signal line 178, and the glue pump 182 is actuated when the elevated portion 171 of the cam 170 moves underneath the follower 169. Adhesive is thus applied to the deposited blank B.

It may now be assumed that the feeder moves from the magazine to the die without a blank, a condition illustrated in FIGS. 18, 19 and 20. The absence of a blank at the cup 95 causes air to enter the cup 95 as a result of which the vacuum in the duct 57 and in the signal line 178 drops, as is also indicated by the pointer of the vacuum gauge 185. The vacuum in the line 178 is insufficient to pull in the plunger 177 which remains in projected position under the action of the spring 193.

The carriage 174 remains in the left position while the follower 169 climbs from the depressed portion 187 of the cam onto the intermediate portion 188, in which position the shoulder 192 of the carriage comes within the reach of the catch 189. When the control valve 186 is subsequently turned into cup-venting position, as shown in FIG. 19, resulting in an increase in the vacuum in the line 178 due to the fact that passage of atmospheric air into the vacuum line 56 is now interrupted, the servomotor 175 is blocked by the catch 189 from moving the carriage 174 into pump actuating position. When the elevated portion 171 of the cam lifts the platform 163, the pump actuator 181 clears the top surface 180 of the carriage and no adhesive is pumped.

Thus the low vacuum signal of FIG. 18, resulting in movement of the carriage 174 to the left, is stored by the cam and catch mechanism which locks the carriage in the non-actuating position during the period the signal pressure is changed by the actuation of the control valve 186.

The position of the elements in FIG. 13 corresponds to the condition shown in FIG. 18. FIG. 14 shows the actuation of the pump and corresponds to FIG. 17. FIG. 15 shows the carriage locked and the plunger actuator 181 beyond the end of the top surface 180, the condition illustrated in FIG. 20.

The control and power circuits of the machine are shown in FIG. 23. A source 194 of power feeds the drive motor 12 and the motor 195 of the hydraulic pump 86 through leads 196, 197, make contact 198 of a relay 199, and lead 200.

The relay circuit is preferably a low voltage circuit extending from a low voltage source 201 through lead 202, relay winding 203, lead 204, a pair of parallel make and break contacts 205 and 206, respectively, lead 207, starter switch 208 and lead 209 back to the source 201.

The break contact 206 is incorporated in a cam switch 210 (FIG. 12) whose arm and follower 211 rests on a cam 212 on the crank shaft 23. The cam 212 is so shaped that the break contact 206 remains closed during the major portion of the revolution of the shaft, but is broken during a fraction of the shaft revolution corresponding to the entry of the plunger into the die.

The make contact 205 is incorporated in a switch 213 on top of the framework 11 (FIGS. 10 and 11) behind the pneumatic plunger actuator assembly. A cam or wedge 214 is mounted on the piston plate 139 and actuates the switch during the period the plunger 105 enters, and remains in, the die. During this period the make contact 205 closes and completes the circuit.

The circuit thus remains completed during the major portion of the revolution of the shaft 23 during which the break contact 206 remains closed while the plunger is outside the die. The contact 205 is broken during the phase of the operation during which the plunger enters the die, but entry of the plunger causes actuation of the switch 213 which closes make contact 205 and keeps the relay circuit unbroken.

If for some reason, for example accidental feeding of two blanks, prevents the plunger from entering the die, the relay circuit is automatically interrupted because of

failure of the switch 213 to operate. The relay 199 drops its armature and the motors 12 and 195 stop and prevent damage to the machine.

What is claimed is:

- 5 1. A machine for forming a glued box from a flat blank, the machine comprising, in combination, a folding die; a plunger mounted for reciprocating movement into and out of said die; a glue head having a discharge aperture therein, said glue head being mounted in advance of the throat of the die in the path of blanks about to enter the die and with its discharge aperture aimed to face a blank moving towards the die; means for arresting a box blank in a position in which the blank overlies the throat of the die and a portion of the blank engages said head and overlies said discharge aperture; blank advancing means for moving a flat blank into engagement with said head and said blank arresting means; a source of liquid adhesive; means for feeding a measured quantity of adhesive; duct means connecting said source to said feeding means and said feeding means to said head; power means for reciprocating said plunger; and means timed with respect to said plunger motion for actuating said feeding means at a moment prior to the insertion of the blank into said die throat by said plunger.
- 10 2. A machine for forming a glued box from a flat blank, the machine comprising, in combination, a folding die; a plunger mounted for reciprocating movement into and out of said die; a glue head having a discharge aperture therein, said glue head being mounted in advance of the die throat in the path of blanks about to enter the die and with its discharge aperture directed to face a blank moving towards the die; blank advancing means for moving a flat blank against said head into a partially folded position in which the blank overlies the die throat
- 15 and the folded portion of the blank engages said head and overlies said discharge aperture; means for arresting the blank in the position in which the blank overlies the die and a portion of the blank overlies said discharge aperture; a source of liquid adhesive; a positive displacement pump; duct means connecting said source to said pump and said pump to said head; power means for reciprocating said plunger; and means timed with respect to said plunger motion for actuating said pump at the moment the blank is arrested prior to engagement by said plunger.
- 20 3. A machine for forming a glued box from a flat blank, the machine comprising, in combination, a folding die; a glue head having a discharge aperture therein, said glue head being mounted in advance of the die in a position to deflect a portion of a blank being advanced towards said die; means for advancing a flat box blank towards said die; means for arresting said blank in a position in which the blank overlies the die and a folded portion of the blank overlies said discharge aperture at the end of the stroke of said advancing means; a source of liquid adhesive; means for feeding a measured quantity of adhesive; duct means connecting said source with said feeding means and said feeding means with said head; and means timed with respect to said blank advancing means for actuating said feeding means at a moment prior to the engagement of the blank by the plunger; at which moment the blank is substantially at rest.
- 25 4. A machine for forming a glued box from a flat blank, the machine comprising, in combination, a folding die; a glue head having a discharge aperture therein, said glue head being mounted in advance of the die; means for advancing a flat box blank toward said die partially past said glue head; means for arresting said blank in a position in which the blank overlies the die and a portion of the blank overlies said discharge aperture; a source of liquid adhesive; means for feeding a measured quantity of adhesive; duct means connecting said source with said feeding means and said feeding means with said head; plunger means for forcing said blank into said die, thereby folding it into box shape; and means timed with

respect to said plunger means for actuating said feeding means at a moment prior to engagement of the blank by the plunger at which moment the blank is substantially at rest.

5. A machine for forming a glued box from a flat blank, the machine comprising, in combination, a folding die; mechanism for moving a blank to, and through said die to fold the blank into box form; a glue head having a discharge aperture therein, said glue head being mounted above the die in the path of the blank into the die so as to be engaged by a portion of the blank, the path being substantially in line with the die axis; means for arresting a box blank in a position in which the blank overlies the die and a portion of the blank overlies the discharge aperture; a source of liquid adhesive; means for feeding a measured quantity of adhesive; duct means connecting said source to said feeding means and said feeding means to said head; and means timed with respect to said blank moving means for actuating said feeding means at that moment prior to insertion of the blank into the die at which the blank is substantially at rest.

6. A machine for forming a glued box from a flat blank, the machine comprising, in combination, a folding die comprising prefolding elements for folding certain portions of the blank into an angular position with respect to the remainder of the blank, and main folding elements forming a throat for folding the blank into box form; a glue applicator having a discharge aperture therein, said glue applicator being mounted in advance of said main folding elements in a location in which its discharge aperture lies immediately underneath the position of a prefolded blank portion; mechanism for moving a blank past said prefolding and main folding elements of said die; means for arresting the blank in a position in which the blank overlies said throat and the prefolded portion of the blank overlies said discharge aperture; a source of liquid adhesive; means for feeding a measured quantity of adhesive; duct means for connecting said source to said feeding means, and said feeding means to said head; and means timed with respect to the blank moving means for actuating said feeding means at a moment at which the blank is substantially at rest above said throat.

7. A machine for forming a glued box from a flat blank, the machine comprising, in combination, a folding die comprising main folding elements forming a throat for folding the blank into box form; a glue head shaped as a prefolding element for engaging and folding a portion of the blank into an angular position with respect to the remainder of the blank, said glue head having a discharge aperture therein and being mounted above said main folding elements in a location in which it engages a portion of the blank and its discharge aperture lies immediately underneath the position of the prefolded blank portion; mechanism for moving a blank first into engagement with said glue head and then into and through the throat of said die; means for arresting the blank in a position in which the blank overlies said throat and the prefolded portion of the blank overlies said discharge aperture; a source of liquid adhesive; means for feeding a measured quantity of adhesive; duct means for connecting said source to said feeding means, and said feeding means to said head; and means timed with respect to the blank moving means for actuating said feeding means at a moment at which the blank is substantially at rest above said throat.

8. A machine for forming a glued box from a flat blank, the machine comprising, in combination, a folding die comprising prefolding elements for folding certain glue panels of the blank into an angular position with respect to the remainder of the blank, and main folding elements forming a throat for folding the blank into box form; four glue applicators, each applicator having a discharge aperture therein, said applicators being mounted above said main folding elements in a loca-

tion immediately underneath the position of the prefolded glue panels; mechanism for moving a blank past said prefolding elements and through said throat of the die; means for arresting the blank in a position in which the blank overlies said throat and the prefolded glue panels overlie the discharge apertures of said applicators; a source of liquid adhesive; means for feeding a measured quantity of adhesive; duct means for connecting said source to said feeding means and said feeding means to said applicators; and means timed with respect to the blank folding means for actuating said feeding means at a moment at which the blank is substantially at rest above said throat.

9. A machine for forming a glued box from a flat blank, the machine comprising, in combination, a folding die comprising main folding elements forming a throat for folding the blank into box form; four glue heads shaped as prefolding elements for engaging and folding portions of the blank into an angular position with respect to the remainder of the blank, said glue heads having a discharge aperture therein and being mounted above said main folding elements in a location in which the respective discharge apertures lie immediately underneath the position of the prefolded blank portions; mechanism for moving a blank into engagement with said glue heads and then into and through the die; means for arresting the blank in a position in which the blank overlies said throat and the prefolded glue panels overlie the discharge apertures in said heads; a source of liquid adhesive; means for feeding a measured quantity of adhesive; duct means for connecting said source to said feeding means and said feeding means to said heads; and means timed with respect to the blank folding means for actuating said feeding means at a moment at which the blank is substantially at rest above said throat.

10. A machine for forming a glued box from a flat blank comprising four glue panels, the machine comprising, in combination, a folding die including main folding elements forming a throat for folding the blank into box form; four glue heads, each head having a discharge aperture therein, said heads being mounted above said main folding elements; prefolding means above said main folding elements in a position to engage and fold said glue panels with respect to the remainder of the blank; means for arresting a blank above the throat of the die in a position in which the prefolded glue panels overlie the glue heads; a blank feeder for moving a flat blank past said prefolding means into engagement with said arresting means; a source of liquid adhesive; means for feeding a measured quantity of adhesive; duct means for connecting said source to said feeding means, and said feeding means to said heads; a plunger timed with respect to said blank feeder for moving said blank from said arresting means into the throat of said die; and means timed with respect to said blank feeder for actuating said adhesive feeding means at a moment prior to engagement by said plunger.

11. A machine for forming a glued box from a flat blank comprising a glue portion, the machine comprising, in combination, a folding die; a glue head having a plurality of discharge apertures therein, arranged in a pattern, said glue head being mounted above the die; means for advancing a blank towards said glue head and from said glue head into said die; means for arresting the blank at said head in a position in which the glue portion overlies the head, but marginally extends beyond said pattern, so as to leave a glue-free margin between the edge of the pattern and the edge of the blank portion overlying the glue head; a source of liquid adhesive; a positive displacement pump for feeding a measured quantity of adhesive; duct means connecting said source to said pump and said pump to said head; and means timed with respect to said blank advancing means for actuating said pump at a moment at which the blank is arrested.

12. A machine for forming a glued box from a flat blank, the machine comprising, in combination, a folding die comprising prefolding elements for folding certain portions of the blank into an angular position with respect to the remainder of the blank, and main folding elements forming a throat for folding the blank into box form; a glue head having a plurality of discharge apertures therein, arranged in a pattern, said glue head being mounted above said main folding elements in a position in which said pattern lies immediately underneath a prefolded blank portion engaged by a prefolding element; mechanism for moving a blank first into engagement with said prefolding elements and then through the throat of said die; means for arresting the blank in a position in which the prefolded portion of the blank overlies, but marginally extends beyond, said pattern, so as to leave a glue-free margin between the edge of the pattern and the edge of the blank portion overlying it; a source of liquid adhesive; a positive displacement pump for feeding a measured quantity of adhesive; duct means for connecting said source to said pump, and said pump to said head; and means timed with respect to the blank moving means for actuating said feeding means at a moment at which the blank is arrested.

13. A machine for forming a glued box from a flat blank, the machine comprising, in combination, a folding die comprising prefolding elements for folding certain glued panels of the blank into an angular position with respect to the remainder of the blank, and main folding elements forming a throat for folding the blank into box form; four glue heads, each head having a plurality of discharge apertures therein, arranged in a pattern, said glue heads being mounted above said main folding elements in a position in which said pattern lies immediately underneath the prefolded glue panels engaged by said prefolding elements; blank advancing means for moving a flat blank to, and into engagement with, said prefolding elements to prefold said glue panels; means for arresting the blank in the position in which said prefolded glue panels overlie, but marginally extend beyond, the respective pattern, so as to leave a glue-free margin between the edge of the pattern and the edge of the glue panel overlying it; a source of liquid adhesive; means for feeding a measured quantity of adhesive; duct means for connecting said source to said feeding means, and said feeding means to said heads; a plunger timed with respect to said blank advancing means for moving said blank from said arresting means into the throat of said die; and means timed with respect to said advancing means for actuating said adhesive feeding means at a moment at which the blank is arrested.

14. A machine for forming a glued box from a flat blank comprising at least two glue panels, the machine comprising, in combination, a folding die comprising main folding elements forming a throat for folding the blank into box form; at least two glue heads, each head having a discharge aperture therein, said heads being mounted above said main folding elements; blank advancing means for moving a flat blank to, and into engagement with, said glue heads, the motion of the blank advancing means being sufficiently far that the glue heads fold the glue panels into an angular position with respect to the remainder of the blank; a source of liquid adhesive; means for feeding a measured quantity of adhesive; duct means for connecting said source to said feeding means, and said feeding means to said heads; a plunger timed with respect to said blank advancing means for moving said blank from said glue heads into the throat of said die; and means timed with respect to said plunger for actuating said feeding means at a moment prior to engagement of the blank by said plunger.

15. A machine for forming a glued box from a flat blank comprising four glue panels, the machine comprising, in combination, a main folding die forming a throat for folding a blank into box form; four glue heads, each head having a discharge aperture therein, said heads be-

ing mounted above said main die; blank advancing means including a suction cup for moving a flat blank into engagement with said glue heads into a position sufficiently far towards the die throat that the glue heads fold the glue panels into an angular position with respect to the remainder of the blank; means for arresting a blank in a position in which the glue panels of the blank are angularly folded and overlie the respective discharge apertures; a source of liquid adhesive; means for feeding a measured quantity of adhesive; duct means for connecting said source to said feeding means, and said feeding means to said heads; a plunger timed with respect to said blank advancing means for moving said blank from said heads into the throat of said die; and means timed with respect to said plunger for actuating said feeding means at a moment at which the blank is engaged by said arresting means.

16. A machine for forming a glued box from a flat blank comprising at least two glue panels, the machine comprising, in combination, a main folding die forming a throat for folding a blank into box form; at least two glue heads, each head having a plurality of discharge apertures therein, arranged in a pattern, said glue heads being mounted above said throat; blank advancing means including a suction cup for moving a flat blank into engagement with, and partially beyond, the glue heads to prefold the glue panels into an angular position with respect to the remainder of the blank; a source of liquid adhesive; means for feeding a measured quantity of adhesive; duct means for connecting said source to said feeding means, and said feeding means to said heads; means for arresting a blank into a position in which the prefolded glue panels of the blank overlie the respective discharge apertures, the pattern of the discharge apertures being smaller than the glue panel overlying it so as to leave a marginal area of the respective glue panel free from adhesive; a plunger timed with respect to said blank advancing means for moving said blank into the throat of the die; and means timed with respect to said plunger for actuating said feeding means at a moment prior to engagement of the blank by said plunger.

17. A machine for forming a glued box from a flat blank, the machine comprising, in combination, a folding die; a plunger movable into and out of said die; a glue head including a glue discharge aperture, said head being mounted above said die; a blank feeder for feeding a blank to, and depositing said blank above, said die in a position of exposure to said glue discharge aperture; a source of liquid adhesive; means including ducts for feeding a measured quantity of adhesive from said source to said head; power means for operating said blank feeder, said adhesive feeding means and said plunger in timed sequence, said adhesive feeding means being operated after release of the blank by said blank feeder; means responsive to the absence of a blank in the blank feeder for producing a control signal; means for storing said signal until after the moment the blank is normally released by the blank feeder; and means responsive to said signal storing means for rendering said adhesive feeding means inoperative and operative respectively, depending on the presence, and absence, of a control signal.

18. A machine for forming a glued box from a flat blank, the machine comprising, in combination, a folding die; a plunger movable into and out of said die; a glue head including a glue discharge aperture, said head being mounted above said die; a pneumatic blank feeder for feeding a blank to, and depositing said blank above, said die in a position of exposure to said glue discharge aperture, said blank feeder comprising a suction cup, a source of vacuum, and valve means for controlling the application and relief, respectively, of vacuum to said suction cup; a source of liquid adhesive; means including ducts for feeding a measured quantity of adhesive from said source of adhesive to said head; power means for operating said blank feeder, said valve means, said adhesive

feeding means and said plunger in timed sequence, said adhesive feeding means being timed to operate after relief of the vacuum at said suction cup and deposition of the blank by said blank feeder; means responsive to the absence of a full vacuum at said suction cup during the feeding portion of the blank feeder motion for producing a control signal; means for storing said signal until after the moment the vacuum is normally relieved by said valve means; and means responsive to said signal storing means for rendering said adhesive feeding means inoperative and operative, respectively, depending on the presence, and absence, of a control signal.

19. A machine for forming a glued box from a flat blank, the machine comprising, in combination, a folding die; a plunger movable into and out of said die; a glue head including a glue discharge aperture, said head being mounted above said die; a pneumatic reciprocating blank feeder for feeding a blank to, and depositing said blank above, said die in a position of exposure to said glue discharge aperture, said feeder comprising a suction cup, a source of vacuum, and valve means for applying vacuum to said suction cup during the feed stroke and relieving the vacuum during the return stroke of the blank feeder; a source of liquid adhesive; a glue pump including ducts for feeding a measured quantity of adhesive from said source of adhesive to said head; power means for operating said blank feeder, said valve means, said glue pump and said plunger in timed sequence, said glue pump being timed for operation after relief of the vacuum by said valve at said suction cup and deposition of the blank by said blank feeder; means responsive to the absence of a full vacuum at said suction cup during the feeding stroke of the blank feeder for producing a control signal; means for storing said signal until after the moment the vacuum is normally relieved by said valve means; and means responsive to said signal storing means for rendering said glue pump inoperative and operative, respectively, depending on the presence, and absence, of a control signal.

20. A machine for forming a glued box from a flat blank, the machine comprising, in combination, a folding die; a plunger movable into and out of said die; a glue head including a glue discharge aperture, said head being mounted above said die; a pneumatic reciprocating blank feeder for feeding a blank to, and depositing said blank above, said die in a position of exposure to said glue discharge aperture, said feeder comprising a suction cup, a source of vacuum, and valve means for applying vacuum to said suction cup during the feed stroke and relieving the vacuum during the return stroke of the blank feeder; a source of liquid adhesive; a glue pump including ducts for feeding a measured quantity of adhesive from said source of adhesive to said head; power means for operating said blank feeder, said valve means, and said plunger in timed sequence; means responsive to the absence of a full vacuum at said suction cup during the feeding stroke of the blank feeder for producing a control signal; drive means for actuating said glue pump by said power means in timed relationship with respect to said plunger movement, said drive means including an element for engaging and disengaging the drive means; means for storing said signal until after the moment the vacuum is normally relieved by said valve means; and means responsive to said signal storing means for actuating said element to engage and disengage the drive means depending on the absence, and presence, of a control signal, respectively.

21. A machine for forming a glued box from a flat blank, the machine comprising, in combination, a folding die; a plunger movable into and out of said die; a glue head including a glue discharge aperture, said head being mounted above said die; a pneumatic reciprocating blank feeder for feeding a blank to, and depositing said blank above, said die in a position of exposure to said glue discharge aperture, said feeder comprising a suction cup, a source of vacuum, and valve means for applying vacuum to said suction cup during the feed stroke and

relieving the vacuum during the return stroke of the blank feeder; a source of liquid adhesive; a glue pump including ducts for feeding a measured quantity of adhesive from said source of adhesive to said head; power means for operating said blank feeder and said plunger in timed sequence; a cam driven by said power means; a cam follower engaging said cam; a servo-motor responsive to the presence, and absence, respectively, of a vacuum at said suction cup; a movable element on said follower, said element being connected to said servo-motor for movement into one position and another depending on the response of the servo-motor to an increase and decrease in the vacuum, respectively, said element being mounted to engage the feed pump in one position and disengage the feed pump in the other position; a catch for retaining said element in the no-vacuum position, said catch being so mounted as to be operative when the follower rests on an elevated position of the cam and to be inoperative when the follower rests on a depressed portion of the cam.

22. A device as set forth in claim 21 in which said cam has a first portion of minimum elevation, a second portion of intermediate elevation and a third portion of highest elevation, the follower being so mounted that the catch is rendered operative by a rise of the follower above the first portion and the pump being so mounted that it is operated by a rise of the follower above the second portion.

23. The method of forming a glued box from a flat box blank which comprises, moving the flat blank to, and partially into, a forming die sufficiently far to fold certain blank portions with respect to the remainder of the blank; arresting the partially folded blank; discharging a measured quantity of adhesive under pressure in a pattern against folded portions of the blank while said portions are at rest; then forcing the blank farther into the die to form the box; and then applying compressive force against the glued portions of the box while in the die.

24. In the method of forming a glued box from a flat blank comprising, feeding the blank, applying adhesive, folding the blank, and applying compressive force to the glued portion of the blank, the steps of, first moving the flat blank to, and partially into, a die sufficiently far to fold certain blank portions with respect to the remainder of the blank; arresting the blank in the partially folded position; discharging against folded portions of the blank a pattern of adhesive under pressure while the folded portions are at rest; and then forcing the blank farther into the die to bring the adhesive-coated portions into engagement with other blank portions in box forming relationship.

25. In the method of forming a glued box from a flat blank comprising, feeding the blank, applying adhesive, folding the blank, and applying compressive force to the glued portion of the blank, the steps of, first moving the flat blank to, and partially into, a die sufficiently far to fold certain blank portions with respect to the remainder of the blank; arresting the blank in the partially folded position; discharging against folded portions of the blank a measured quantity of adhesive in a pattern, under pressure while the folded portions are at rest; and then forcing the blank farther into the die to bring the adhesive-coated portions into engagement with other blank portions in box forming relationship.

26. The method of forming a glued box from a flat box blank which comprises, moving the flat blank to, and partially into, a forming die sufficiently far to fold certain blank portions with respect to the remainder of the blank; arresting the partially folded blank; discharging a measured quantity of adhesive under pressure against folded portions of the blank; then advancing a plunger against the blank to force the blank farther into the die to form a box about the plunger; contracting the die about the plunger to apply compressive force against the plunger-backed glued portions of the box; withdrawing

the plunger from the box and bowing in opposite box wall panels to a distance less than the width of the bottom panel of the box; and then ejecting the box by the bottom panel of a second box formed during the next cycle, said second box striking the bowed-in wall portions.

27. A machine for forming a glued box from a flat blank of foldable sheet material, the machine comprising, in combination, means forming a main folding die for folding the blank into box shape; an adhesive applicator mounted above said main die in a position to engage and prefold a portion of the blank with respect to the remainder of the blank when the blank is moved towards said main die in a direction substantially at right angles to the plane of the flat blank, said adhesive applicator comprising a wall having at least one adhesive discharge aperture therein, said wall being inclined at an angle substantially equal to the angle of inclination of said prefolded portion with respect to the remainder of the blank; means for moving a flat blank into a position above the main die into engagement with said applicator partially to prefold said blank; and means timed with respect to said blank moving means for discharging adhesive under pressure through said discharge aperture at the time said blank portion overlies said wall.

28. A machine for forming a glued box from a flat blank of foldable sheet material, the machine comprising, in combination, means forming a main folding die for folding the blank into box shape; a plurality of adhesive applicators mounted above said main folding die in a position to engage and prefold portions of the blank with respect to the remainder of the blank when the blank is moved towards said main die in a direction substantially normal to the plane of the flat blank, each of said adhesive applicators comprising a wall having at least one adhesive discharge aperture therein, said discharge aperture extending in a direction substantially normal to the surface of the prefolded portions of the blank; means for moving a flat blank into a position above said main die into engagement with said applicators partially to prefold said blank; and means timed with respect to said blank moving means for discharging adhesive under pressure through said discharge apertures against the prefolded portions at the time said blank portions overlie said walls.

29. A machine for forming a glued box from a flat blank of foldable sheet material, the machine comprising, in combination, means forming a main folding die for folding the blank into box shape; a plurality of adhesive applicators mounted above said main folding die in a position to engage and prefold portions of the blank with respect to the remainder of the blank when the blank is moved towards said main die in a direction substantially normal to the plane of the flat blank, each of said adhesive applicators comprising a substantially flat front surface having a plurality of adhesive discharge apertures therein, said front surface extending at an angle to the axis of the main die; means for moving a blank into a position above said main die in which said applicators engage and prefold portions of said blank, in which prefolded position said portions overlie said front surfaces; and means timed with respect to said blank moving means for discharging adhesive under pressure through said discharge apertures against the prefolded portions at a time said portions overlie said front surfaces.

30. A machine for forming a glued box from a flat blank of foldable sheet material, the machine comprising, in combination, means forming a main folding die for folding the blank into box shape; a plurality of adhesive applicators mounted above said main folding die in a position to engage and prefold portions of the blank with respect to the remainder of the blank when the blank is moved towards said main die in a direction substantially normal to the plane of the flat blank, each of said adhesive applicators comprising a front surface having at

least one adhesive discharge aperture therein, the axis of which is inclined to the imaginary plane normal to the die axis; means for moving a blank into a position above said main die in which position said applicators engage and prefold certain blank portions with respect to the remainder of the blank in which prefolded position said portions overlie the discharge aperture substantially at right angles to the aperture axis; a catch for engaging and arresting relatively to said applicators a blank deposited between said applicators by said blank moving means; and means timed with respect to said blank moving means for discharging adhesive under pressure through said applicators against said blank portions at the time said blank portions overlie said front surfaces.

31. A machine for forming a glued box from a flat blank of foldable sheet material comprising glue flaps articulated to the remainder of the blank along glue flap fold lines, the machine comprising, in combination, means forming a main folding die for folding the blank into box shape; a plurality of adhesive applicators, one for each glue flap, mounted in advance of said main folding die in a position to engage said flaps before the blank enters said main die, each of said adhesive applicators including a front surface having at least one adhesive discharge aperture therein, said discharge aperture having an axis extending at an angle to the axis of the main die; a blank mover for moving the blank into a position above said main die into engagement with said applicators to prefold said glue flaps, said mover comprising blank contacting elements having substantially parallel outer edges for engaging and backing up said blank adjacent said flap fold lines, the outer edges of said elements being spaced less than the distance between the front surfaces of opposite applicators; and means timed with respect to said mover for discharging a measured volume of adhesive through said discharge apertures against said prefolded flaps after engagement with and prefolding of the flaps by said applicators.

32. A machine for forming a glued box from a flat blank of foldable sheet material comprising glue flaps articulated to the remainder of the blank along glue flap fold lines, the machine comprising, in combination, means forming a main folding die for folding the blank into box shape; a plurality of adhesive applicators mounted in advance of said main folding die in a position to engage said flaps before the blank enters said main die, each of said adhesive applicators including a front surface having at least one adhesive discharge aperture therein, the front surface of opposite applicators being inclined with respect to each other to form a V; a blank mover for moving the blank into engagement with said applicators into the said V, said mover comprising blank contacting elements having substantially parallel outer edges for engaging and backing up said blank adjacent said flap fold lines, the outer edges of said elements being spaced less than the distance between the front surfaces of opposite applicators to enter the V space between opposite applicators; and means timed with respect to said mover for discharging adhesive through said discharge apertures against said flaps after the blank has entered the V and the flaps are engaged by said applicators.

33. A system for applying adhesive to folding box blanks comprising, in combination, a receptacle for storing a supply of adhesive under atmospheric pressure; an applicator head comprising a housing having a plurality of discharge apertures in a wall thereof arranged in a discharge pattern; a positive displacement pump, including duct means, for withdrawing adhesive from said receptacle and feeding such withdrawn adhesive under pressure to said head for discharge through said apertures, the displacement volume of the pump being so dimensioned with respect to size of said apertures as to extrude a single bead of liquid adhesive through each said aperture for each single pump stroke; means for moving box blanks past said apertures at predetermined intervals; and means

timed with respect to said moving means for actuating said pump once for each blank.

34. A system for applying adhesive to folding box blanks comprising, in combination, a receptacle for storing a supply of adhesive under atmospheric pressure; an applicator head comprising a housing having a plurality of discharge apertures in a wall thereof arranged in a discharge pattern; a positive displacement pump, including duct means, for withdrawing adhesive from said receptacle and feeding such withdrawn adhesive under pressure to said head for discharge through said apertures, the displacement volume of the pump being so dimensioned as to extrude a single bead of liquid adhesive through each said aperture for a single pump stroke; means for moving box blanks past said apertures at predetermined

15

intervals; means timed with respect to said moving means for actuating said pump once for each blank; a plurality of pins inside said housing, said pins being adapted to be moved into said apertures to close them, and out of said apertures to permit discharge of adhesive therethrough; and manual means for so moving said pins.

UNITED STATES PATENT OFFICE
CERTIFICATE OF CORRECTION

Patent No. 3,038,389

June 12, 1962

Edward J. Pagendarm

It is hereby certified that error appears in the above numbered patent requiring correction and that the said Letters Patent should read as corrected below.

In the drawings, Fig. 16, left-hand portion, for the indistinct letter, read -- B --; column 1, line 12, for "poritons" read -- portions --; line 36, for "exposed" read -- expose --; column 8, line 29, for "extmple" read -- example --; column 11, line 67, for "latter" read -- later --; same line 67, strike out "of"; column 17, line 70, strike out "is engaged"; column 18, line 53, for "feedirng" read -- feeding --; column 21, line 71, for "portions" read -- a portion --; column 22, line 72, before "size" insert -- the --.

(SEAL)   Signed and sealed this 25th day of December 1962.
